1 Claim

ABSTRACT OF THE DISCLOSURE

A shampoo preparation consisting of a mixture comprising salicylic acid, an anionic surface active agent, alkyl esters of phthalic acid and/or adipic acid, and optionally water is provided.

The present invention relates to a shampoo preparation consisting of a mixture which comprises salicylic acid, anionic wetting agents and preferably also water.

Such shampoo preparations are previously known. They have been used for treating hair and the roots thereof for the purpose of cleaning the same. The most active constituents of such a preparation is the anionic wetting agent. The function of the salicylic acid is to combat micro-organisms, primarily fungi. It also has a keratolytic effect, i.e. it is capable of breaking up hard skin.

It has now been shown that the effect of the salicylic acid in particular can be increased considerably if certain fat dissolving organic solvents are added to the shampoo. Particular examples of such agents are lower aliphatic esters of any of the two dibasic acids phthalic acid and adipic acid, or mixtures thereof. These solvents have a good therapeutic acceptance and a low degree of volatility which is of importance with respect to fire risk and odour. Their most important property, however, is that they have been shown surprisingly capable, when coming into contact with the skin, of softening the wax-like layers of skin fat which normally cover the capillary matrix, so that the scalp is cleaned more effectively. Consequently the salicylic acid, in turn, acts keratolytically.

The invention is therefore characterized in that, for this purpose, one or more lower alkyl esters of phthalic acid and/or adipic acid are incorporated into the shampoo preparation.

The percentages of the various constituents in the shampoo preparation may be varied within wide limits. Usually, however, the percentage of salicylic acid lies between 0.1 and 5 percent by weight, the percentage of anionic wetting agents between 10 and 80 percent by weight and the percentage of fat dissolving organic solvent between 1 and 20 percent by weight. If the shampoo preparation contains water, which is usually the case, the percentage thereof does not usually exceed 90 percent by weight. All the above percentages are calculated on the total weight of the shampoo preparation.

Examples of appropriate solvents according to the invention are: dimethyl-phthalate, diethyl-phthalate, and di-n-butyl-phthalate, and, further, dimethyl-adipate, diethyl-adipate, diisopropyl-adipate and di-n-butyl-adipate. Particularly good results have been obtained with dimethyl-phthalate.

Examples of anionic wetting agents are dioctyl-sodium sulphosuccinate, sodium laurylsulphoacetate, sodium laurylsulphate, sodium tetradeclsulphate. Salicylic acid may also be introduced into the composition in the form of a derivative hydrolyzable thereto, e.g. in the form of an ester, which forms the free acid in the presence of water.

2

In addition to the above ingredients obligatory, the shampoo preparation according to the foregoing may also include other facultative constituents which give specific effects. Examples of such constituents are cetanol, lanolin and glycerylmonostearate, which may be added as consistency regulators. Lecithin may be added to improve the skin sensitivity of the agent. Further, thickening agents, perfumes and colouring agents may be added, as well as agents which heighten the antiseptic effect of the salicyclic acid, e.g. benzoic acid, lower alkyl esters of p-hydroxybenzoic acid and hexachlorophenol.

The shampoo preparation according to the invention has been shown to give good results if the hair subsequent to being treated with the same is treated with an antiseptic hair wash. An example of such a wash is one which consists of a solution or dispersion comprising pantothenol, whereby it is particularly emphasized that extraordinarily satisfactory results can be obtained if the hair wash also includes surface active quaternary ammonium compounds having an antimicrobial effect.

The invention will now be clarified by examples.

EXAMPLE 1

A shampoo preparation was made up by mixing the following constituents:

	G.
Salicylic acid, powder	2
Dimethyl phthalate	5
Monostearine	2.5
30 Cetanol	2.5
Sodium dodecylsulphate	10
Sodium dodecylbenzenesulphonate	50
Water to 100 g.	

The shampoo preparation when applied to hair and the capillary matrix, was shown to possess an extraordinarily good cleaning and softening effect.

EXAMPLE 2

A shampoo preparation was made up by mixing the following constituents:

	G.
Salicylic acid, powder	2
Ethyl-p-oxy-benzoate	1
45 Isopropyl adipate	6
Triethanolamine laurylsulphate	35
Water, perfume and colouring agent to 100 g.	

The shampoo preparation when applied to hair and the capillary matrix was shown to possess an extraordinarily good cleaning and softening effect.

EXAMPLE 3

A shampoo preparation was made up by mixing the following constituents:

	G.
Salicylic acid	20
Dimethyl phthalate	50
Turkish red oil	720
60 Pur-cellin oil (Pur-cellin oil is the same as "PCL liquid" which is a branched chain alkyl fatty acid ester with low solidification point. It is an ester of the fatty acid	

65	$\begin{array}{c} \text{H}_3\text{C}-\text{CH}_2-\text{CH}_2-\text{CH}_2-\text{CH}-\text{COOH} \\ \\ \text{C}_2\text{H}_5 \end{array}$	
70	most probably with a simple alcohol such as ethyl alcohol or isopropyl alcohol. Dragoco Inc., Totowa, N.J.)	40
Oleyl alcohol		30
Glycerol		30
Water and perfume oil to 1,000 g.		

The shampoo preparation when applied to hair and the capillary matrix, was shown to possess an extraordinarily good cleaning and softening effect.

EXAMPLE 4

A shampoo preparation was made up by mixing the following constituents:

Salicylic acid	2	G.
Dimethyl phthalate	10	
Sodium chloride	2	
Standapol S (Standapol S is a trademark for tri-ethanol lauryl sulfate. Standard Chem. Prod., Hoboken, N.J.)	35	
Water and perfume to 100 g.		

The shampoo preparation when applied to hair and capillary matrix, was shown to possess an extraordinarily good cleaning and softening effect.

EXAMPLE 5

A shampoo preparation was made up by mixing the following constituents:

Salicylic acid, fine powder	2	G.
Dimethyl phthalate	5	
Sodium lauryl sulphate	20	
"Coconut" monoethanolamide	1	
Propylene glycol monostearate	2	
Stearic acid	5	
Water and perfume to 100 g.		

The shampoo preparation when applied to hair and capillary matrix, was shown to possess an extraordinarily good cleaning and softening effect.

What I claim is:

1. The method of cleaning hair and the roots thereof and softening the wax-like layers of skin fat which normally cover the capillary matrix which comprises shampooing the hair and capillary matrix with a shampoo preparation consisting of a mixture comprising 0.1-5% of salicylic acid, 1-20% dimethyl phthalate, 10-80% of an anionic wetting agent selected from the group consisting of dioctyl- sodium sulphosuccinate, sodium laurylsulphoacetate, sodium laurylsulphate, and sodium tetradecylsulphate, and 0-90% of water.
